CLAIM

The ornamental design for a front panel of a packaging container for a lighter, as shown and described.

DESCRIPTION

FIG. 1 is a perspective view of a front panel of a packaging container for a lighter showing our new design;

FIG. 2 is a front elevational view thereof;

FIG. 3 is a left side elevational view thereof, the right side elevational view being a mirror image thereof;

FIG. 4 is a top plan view thereof, the bottom plan view being identical to the top plan view; and,

FIG. 5 is a rear elevational view thereof.

The broken line showing of container is for illustrative purpose only and forms no part of the claimed design.
